AURY G. COES, OF WORCESTER, MASSACHUSETTS.

Letters Patent No. 95,988, dated October 19, 1869.

IMPROVEMENT IN MACHINES FOR GRINDING CYLINDRICAL-FLUTED CUTTERS.

The Schedule referred to in these Letters Patent and making part of the same.

To all to whom these presents shall come:

Be it known that I, AURY G. COES, of the city and county of Worcester, and Commonwealth of Massachusetts, have made an invention of a new and useful Machine for Grinding Cylindrical-Fluted Cutters for "milling"-machines, &c.; and do hereby declare the following to be a full, clear, and exact description thereof, due reference being had to the accompanying drawings, making part of this specification, and in which—

Figure 1 is a plan,

Figure 2, a front elevation,

Figure 3, a vertical and transverse section, and

Figure 4, a vertical central and longitudinal section of a machine embodying the features of my invention.

The invention herein described, and constituting the subject-matter of these Letters Patent, relates to means for grinding or sharpening the cutting-edges of fluted cutters, now generally used in milling-machines, for reducing metals to an even and given face.

Although machines have heretofore been devised for the purpose named, they have been so crude and imperfect in construction, and unreliable in operation, that in many establishments these cutters are at the present day sharpened by hand, at much expenditure of time and labor.

My present invention consists, first, in the adoption of a head-stock, mounted upon a suitable frame or standard, and provided with an arbor carrying an emery-wheel or grindstone, very much after the manner of ordinary turning-lathes, the cutter to be ground being supported upon a travelling reciprocating carriage, disposed below such emery-wheel, whereby the wheel is caused to traverse in opposite directions the cutting-edge of each tooth of the cutters, minor conditions of the invention consisting in a means of regulating the height of the carriage, and consequently, of the cutter, with respect to the wheel, as well as the horizontal adjustment of the same, and of producing an endwise reciprocation of the arbor and wheel, in order to obviate uneven wear and scoring of the latter, and of the teeth of the cutter, a guiding-stop or abutment being combined with the travelling-carriage, in order to insure the proper position of the cutter, the whole being as hereinafter explained.

The drawings which accompany this specification, and which illustrate my invention, represent a machine, as composed, first, of a head-stock, A, mounted upon a suitable standard or table, B, and provided with an arbor, C, such arbor, at its working-end, being provided with an emery-wheel or grindstone, c, such constituent parts being constructed and arranged

in manner similar to like parts in turning-lathes of ordinary manufacture, with the exception that the length of the journals of the arbor is somewhat in excess of that of the bearings which enclose them, in order to permit of end-on movements of such arbor, as hereinafter explained.

In pursuance of my invention, I apply to the front of the head-stock A, and below the sharpening-wheel c, in alignment with its path of revolution, and at right angles to the axis of the arbor, two long parallel guides or ways d d, and upon such ways I mount a sliding carriage or rest, e, the necessary lateral reciprocations of such carriage thereupon being effected by means of a rack, f, and pinion g, the former being affixed to the under side of the carriage-platform, and the latter to a horizontal shaft, h, disposed below such platform, and in axial alignment, or thereabout, with the arbor C, before mentioned, the said shaft revolving in a bearing or bracket, i, made within or affixed to one of the ways d.

Revolution of the shaft h, in either direction, will, of course, produce corresponding rectilinear movements of the carriage e in the same direction.

The ways d d are affixed to the machine-standard B in an adjustable manner, by means of slats a' and bolts b', in order that a feed-motion may be obtained toward or away from the sharpening-wheel, such feeding, in the present instance, being effected by screws j j passing through ears k k, formed in the machine-frame.

The vertical adjustment of the carriage permits of the introduction of cutters of varying diameter to the machine, and also is the means whereby the effect of variations in length of the teeth, should any occur, is overcome, since it frequently happens that one tooth is of somewhat different length than its neighbor, and but for some means of compensating for this difference, the sharpening-stone would bear with too much friction upon the long tooth, or would entirely pass over without touching the short one.

l l, in the accompanying drawings, represent two standards or posts, each provided with an upright groove, m, opening upward, these posts being erected upon the top of the platform of the carriage e, and upon opposite sides of its centre, the intervening space being of more than sufficient extent to receive the longest cutter which may be subjected to the action of the machine.

To the standards l l, I swivel, in a suitable manner, two forked bars n n, upon the top of which the journals o o of the cutter-mandrel p rest, such bars supporting and effecting the vertical adjustment of such mandrel, while the grooved posts maintain the proper lateral position of it.

The front and free extremity of each forked bar n

is upheld by a screw, *q*, passed downward through it, and resting upon the top of the carriage-platform; hence it will be apparent that by the aid of these screws and bars the horizontal adjustment of the mandrel and cutter is secured, since it becomes necessary to vary this horizontal position of the mandrel, or its parallelism with respect to the upper surface of the carriage-platform and its supporting-ways, in order to adapt the machine to cutters of a tapering or frusto-conical outline.

We have now seen how the vertical feeding or adjustment of the ways *d d* is effected, and also the horizontal adjustment of the cutter-mandrel, in relation to the carriage-platform which carries it, and in pursuance of my invention it becomes necessary to provide a means of insuring the proper position of each tooth, in its turn, below the sharpening-wheel, in order that the periphery of the wheel shall bear firmly upon its cutting-edge while making a traverse of it.

To this end I erect, upon the front part of the outer way *d*, a standard, or post, *r*, and to the upper part of this post I attach, with an adjustable connection, a bracket, *s*, and to the upper surface of the shelf *t* of such bracket I mount a movable stop-plate or abutment, *u*, the union of the two being effected by a bolt, *v*, passing through a slot, *w*, made in the plate, and screwing into the shelf, by which means the recession or approach of the plate, with respect to the cutter, may be varied and determined according to the width of the sharpening-wheel, and its action upon the teeth of the cutter.

To insure contact of a tooth of the cutter with the guiding-plate *u*, I apply, to the outer extremity of one of the journals of the mandrel *p*, a belt, chain, or equivalent object, *y*, such belt being passed once or twice about the journal, and having a weight, *x*, affixed to its opposite and pendent end, the gravity of the weight tending to revolve the mandrel and cutter in a direction toward the stop, and, as a necessary result, serving to hold tightly to it the tooth of the cutter which may at the time be impinging against it.

The variable attachment of the guide-plate *u*, to its point of support, enables me to graduate its position relatively to the sharpening-wheel; hence I am enabled to insure the contact of the two in such respective positions as to secure a uniform wear upon the wheel, according to the width of its periphery, and to obtain the best results in other respects.

The guiding-plate or its equivalent becomes an important feature of the machine, in case a cutter is to be sharpened whose teeth are placed obliquely to its axis, as but for this stop or its equivalent, the sharpening-wheel would leave the face of the tooth at some point in its length, unless the width of the wheel were of sufficient extent to cover the extreme variations of the departure of the tooth from a line parallel to the axis of the cutter, should such cutter travel in union with or in the same path as the carriage *e*.

In practice, it will undoubtedly be found impracticable to employ a sharpening-wheel of sufficient width to accomplish this, and also, which is of more importance, that the action of the wheel upon the cutting-edge of the tooth would not be as favorable, owing to a change in its angle of cut upon such tooth, between the two ends of the latter. Therefore, as above observed, the guiding-plate becomes an important, if not an indispensable feature of my invention.

To provide against creasing of the sharpening-wheel, and consequently of the cutting-face of the cutting-teeth, which, as mechanics will understand, would ensue, did such wheel travel at all times in the same orbital path, I mount a short horizontal shaft, *e*, in bearings *f g*, erected upon the tablet of the ma-

chine-frame, in rear of the head-stock, and in longitudinal alignment with its arbor *C*, such shaft *e* being slowly revolved by a belt travelling about a pulley, *h*, affixed to it.

The forward part of the said shaft *e* carries a cam, *i*, to produce endwise reciprocations of the arbor *C* and of the sharpening-stone, such endwise movement being produced by extending the flange into the channel *j* of a grooved wheel, *l*, mounted upon the rear extremity of the outer journal of the arbor, as represented in fig. 4 of the accompanying drawings.

The pinion-shaft should be supplied with a wrench, *t*, by which to rotate it in either direction.

In operating with the said machine, the cutter-mandrel is to be removed from its support, and the cutter slipped upon it, the mandrel being supplied with a nut, *j*, and screw-thread *k*, for securing the cutter in place thereupon, which being done, the mandrel is returned to place.

The sharpening-wheel is then put in rapid revolution, and the workman, seizing the crank in his right hand, revolves the pinion in such a direction as to produce a traverse movement of the carriage *e* below the sharpening-wheel, which brings the latter in contact with the cutting-teeth of the cutter, and reduces such face to an even and sharp cutting-edge.

The transverse movement of the carriage *e* should be continued until the cutter has been carried entirely beyond reach of the sharpening-wheel, and of the guiding-stop *u*, when such cutter is to be revolved to the extent of one tooth and retracted to its starting-point, which subjects the next successive tooth to the action of the reducing-wheel, these movements being repeated until the teeth of the entire cutter have been acted upon, when such cutter is to be removed, and a new one substituted.

I am aware that for sharpening a certain class of cutters, a machine has been invented, in which an emery-wheel or grindstone has been made to bear upon and grind the surface of the teeth of fluted rollers, in a direction at right angles to the longest plane of such teeth, the grinding-wheel or stone in this instance travelling, while the cutter remained at rest.

This machine, however, is entirely impracticable for sharpening the class of cutters to which mine is applied, as the teeth of such cutters are disposed in such close proximity, one to the other, that the grinding-stone, if applied at right angles to their longest axis, would unavoidably strike the next adjacent tooth, with very injurious results. In fact this old machine was not intended for or susceptible of performing the labor accomplished by that herein explained.

What I claim, therefore, and desire to secure by Letters Patent, is—

1. The combination, with the sharpening-wheel and reciprocating carriage, of the cutter-holding mandrel, arranged in or parallel with the plane of rotation of the wheel, and supported in independently-adjustable bearings, substantially as described, so that the mandrel may be adjusted at either end to bring it into proper position to receive the tapering or other-shaped fluted cutter to be acted upon by the wheel.

2. In combination with the sharpening-wheel, and sliding or reciprocating carriage, and cutter-holding mandrel, arranged in or parallel with the plane of rotation of said wheel, as described, the employment of a guiding-plate or stop, affixed to the stationary part of the machine, and arranged to engage with the cutter-teeth during the reciprocations of the carriage, as set forth.

3. The combination of the sharpening-wheel and

cam, for imparting an endwise motion to its shaft, with the reciprocating carriage and cutter-holding mandrel, arranged to move in or parallel with the plane of rotation of said wheel, substantially as shown and set forth.

4. A machine for grinding and sharpening fluted cutters, in which the vertically-adjustable reciprocating carriage, the cutter-supporting mandrel and its adjustable end-bearings, the revolving sharpen-

ing-wheel, and cam for imparting an endwise motion to the same, and the guiding-plate or stop for holding in position the cutter-teeth, are combined and arranged, with relation to each other, and for joint operation, as herein shown and described.
